AWNING

William B. Kellett, Tucson, Ariz.

Application September 8, 1958, Serial No. 52,535

Term of patent 14 years

(Cl. D21—6)

Fig. 1.

Fig. 2.

Fig. 3.

Figure 1 is a front elevational view of an awning, showing my new design;

Figure 2 is a side elevational view thereof, the opposite side having substantially the same appearance; and

Figure 3 is a cross-sectional view thereof, taken on line 3—3 of Figure 2.

Portions of the drawing figures are diagonally lined to indicate translucency.

I claim:

The ornamental design for an awning, as shown and described.
